(57) **CLAIM**

The ornamental design for a mattress cover, as shown and described.

DESCRIPTION

FIG. 1 is a top elevational view of the mattress cover of the present design;

FIG. 2 is a bottom elevational view of the mattress cover of FIG. 1;

FIG. 3 is a front elevational view of the mattress cover of FIG. 1;

FIG. 4 is a rear elevational view of the mattress cover of FIG. 1;

FIG. 5 is a left side elevational view of the mattress cover of FIG. 1;

FIG. 6 is a right side elevational view of the mattress cover of FIG. 1;

FIG. 7 is a perspective view of the mattress cover of FIG. 1; FIG. 8 is a top elevational view of a mattress cover of the present design in accordance with an another embodiment of the mattress cover;

FIG. 9 is a bottom elevational view of the mattress cover of FIG. 8;

FIG. 10 is a front elevational view of the mattress cover of FIG. 8;

FIG. 11 is a rear elevational view of the mattress cover of FIG. 8;

FIG. 12 is a left side elevational view of the mattress cover of FIG. 8;

FIG. 13 is a right side elevational view of the mattress cover of FIG. 8;

(Continued)

FIG. 14 is a perspective view of the mattress cover of FIG. 8;
 FIG. 15 is a top elevational view of a mattress cover of the present design in accordance with an another embodiment of the mattress cover;
 FIG. 16 is a bottom elevational view of the mattress cover of FIG. 16;
 FIG. 17 is a front elevational view of the mattress cover of FIG. 16;
 FIG. 18 is a rear elevational view of the mattress cover of FIG. 16;
 FIG. 19 is a left side elevational view of the mattress cover of FIG. 16;
 FIG. 20 is a right side elevational view of the mattress cover of FIG. 16;
 FIG. 21 is a perspective view of the mattress cover of FIG. 16;
 FIG. 22 is a top elevational view of a mattress cover of the present design in accordance with an another embodiment of the mattress cover;
 FIG. 23 is a bottom elevational view of the mattress cover of FIG. 22;
 FIG. 24 is a front elevational view of the mattress cover of FIG. 22;
 FIG. 25 is a rear elevational view of the mattress cover of FIG. 22;
 FIG. 26 is a left side elevational view of the mattress cover of FIG. 22;
 FIG. 27 is a right side elevational view of the mattress cover of FIG. 22; and,
 FIG. 28 is a perspective view of the mattress cover of FIG. 22.
 The broken lines shown in the drawings are included for the purpose of illustrating unclaimed portions of the mattress cover and form no part of the claimed design.

1 Claim, 20 Drawing Sheets
